(57) **CLAIM**

The ornamental design for an oral illumination device, as shown and described.

DESCRIPTION

FIG. 1 is a front perspective view of an oral illumination device;

FIG. 2 is a front view thereof;

FIG. 3 is a back view thereof;

FIG. 4 is a side view thereof;

FIG. 5 is an opposing side view thereof;

FIG. 6 is a top view thereof;

FIG. 7 is a bottom view thereof; and,

FIG. 8 is a back perspective view thereof.

The broken lines shown in the drawings depict portions of the oral illumination device that form no part of the claimed design.

1 Claim, 8 Drawing Sheets
